UNITED STATES PATENT OFFICE.

JULIAN G. CAMPAU, OF MONROE, MICHIGAN, ASSIGNOR OF ONE-HALF TO LEO M. CONNELL, OF JACKSON, MICHIGAN.

COMPOUND RAIL.

1,061,726.

Specification of Letters Patent. **Patented May 13, 1913.**

Application filed January 15, 1913. Serial No. 742,230.

ing a half flange and a half web confronting the half web of the first mentioned section with its upper end inclined to correspond to and engage in the recess of the head, the inner face of the last mentioned half web being slightly obtuse to the half flange of the same, and clamp devices operating through the confronting half webs whereby the head is supported and the parts

held under strain when pressure is applied 10 by the clamp devices.

In testimony whereof I affix my signature in presence of two witnesses.

JULIAN G. CAMPAU. [L. S.]

Witnesses:

JOHN V. ERLACHER,
GEORGE J. HARTMAN.
